UNITED STATES PATENT OFFICE.

WILLIAM CLARK MITCHELL, OF SYDNEY, NOVA SCOTIA, CANADA.

EXCAVATING-BUCKET.

No. 925,588.

Specification of Letters Patent.

Patented June 22, 1909.

Application filed December 21, 1908. Serial No. 468,684.

To all whom it may concern:

Be it known that I, WILLIAM CLARK MITCHELL, of Sydney, in the Province of Nova Scotia, Canada, have invented certain new and 5 useful Improvements in Excavating-Buckets, of which the following is a specification.

My invention relates to improvements in excavating buckets of the scoop grab type and the objects of my invention are to provide 10 a simple and effective form of bucket having an unusually wide opening together with a powerful opening and closing action.

Further objects are to reduce the height of the bucket as much as possible and to provide 15 means for adjusting the scoops whereby greater efficiency may be secured in operating in hard or soft material as well as in coarse or fine.

In its construction the bucket is formed of 20 two scoops of suitable character adapted to form a single receptacle or bucket when their front edges are brought into contact. These scoops are suspended from shafts by a combination of arms or links and the power for 25 opening and closing the same is applied through a series of shafts and ropes, the arrangement being such that the scoops as well as oscillating about their common center in opening or closing will also oscillate about 30 other separate centers thereby increasing the power of the digging action.

The general arrangement of the parts is such as to secure a minimum height of structure when the bucket is open, thereby lowering 35 the center of gravity and reducing the tendency of the bucket to overturn to a minimum.

All these and other features of the invention are described more fully in the following 40 specifications and drawings.

In the drawings, Figure 1 is a side elevation of the bucket. Fig. 2 is a vertical section through the same. Fig. 3 is an under view.

In the drawings, like figures of reference 45 indicate corresponding parts in each figure.

Referring to the drawings 1 and 2 represent the scoops or trays of any suitable or convenient design and which are supported from a transversely extending shaft 3 by 50 means of connecting pairs of links 4 and 5 pivoted to the shaft and to the front upper edge of the scoops, the said links being hereinafter referred to as the front links.

The scoops illustrated are substantially in 55 the shape of buckets, the front edges of

which are adapted to meet and form substantially a closed receptacle as hereinafter explained, however, the mechanism may so be adjusted that the bucket will be left partially open to operate as a scoop. 60

In order to give a compound movement to the scoops in opening and closing as herein-after described, triangular links 7 and 8 are pivoted to the front links 4 and 5 as by means of shafts 9 and 10 respectively which 65 extend between the arms of the respective pairs of links 4 and 5. The free inner ends of these triangular links are connected by a transversely extending shaft 11 while their outer ends are pivotally connected by pairs 70 of arms 12 and 13 to suitable projections 12' and 13' on the outer end of the scoops. Provision is made for adjusting the pivoting point of the link bars 12 and 13 by forming sets of apertures 7' and 8' in the triangular 75 links 7 and 8, the said apertures being adapted to receive and journal the pivoting shafts 14 and 15. The scoop is actuated by suitable opening and closing ropes and to journal these swinging pulleys or guide 80 shafts 16 and 17 are provided on the outer end of the shaft 3. Two opening ropes 21 are provided extending at opposite sides of the structure of the bucket, each of the ropes passing through a pulley 17 then around a 85 sheave 18 and then up where the end is secured to the shaft 3. Two closing ropes are likewise provided each of which passes through a pulley 16 then around a sheave 19 secured to the link 4 then around a sheave 20 90 secured to the link 5 and then back to sheave 19 where it is secured.

The operation of the bucket is as follows: A pull on the closing ropes 22 will, of course, draw the lower ends of the arms 4 and 5 95 toward each other causing the front ends of the scoops to swing together. As the ends of the scoops approach each other the free ends of the triangular links 7 and 8 swing down, thereby lowering the rear ends of the 100 scoops and bringing the same into proper position to easily pass through the material which is being excavated. When it is desired to open the bucket the closing line is slackened and an upward pull on the opening 105 rope causes the free ends of the triangular links 7 and 8 to swing up toward the upper ends of the pairs of arms 4 and 5, and at the same time the upper ends of said arms are drawn down toward said links so that a very 110

powerful and quick movement is secured which will open the bucket against considerable resistance.

It will be observed that the compound motion imparted to the buckets by means of the triangular links 7 and 8 is very effective in producing a powerful digging opening and closing action enabling the bucket to dump with great rapidity and to be very effective 10 in digging into the ground. Further than this, if it is desired to make the bucket more in the nature of a scoop the pivoting point of the triangular links 7 and 8 may be adjusted as hereinbefore explained and the bucket 15 will be found to give equal efficiency as a scoop grab when the pivoting points are adjusted between the limits of half and full opening.

As many changes could be made in the 20 above construction and many apparently widely different embodiments of my invention within the scope of the claims, could be made without departing from the spirit or scope thereof, it is intended that all matter 25 contained in these specifications and drawings shall be interpreted as illustrative and not in a limiting sense.

What I claim as my invention is:

1. An excavating bucket including a central shaft, a pair of scoops, front links connecting the shafts to the inner edge of the scoops, triangular links pivoted to the front links having their free ends pivotally connected, the rear links connected to the corners of the triangular links and to the rear of the scoops, and means for opening and closing the buckets.

2. An excavating bucket including a central shaft, a pair of scoops, front links connecting the shafts to the inner edge of the scoops, triangular links pivoted to the front links having their free ends pivotally connected, the rear links connected to the corners of the triangular links and to the rear of the scoops, and means for opening and closing the buckets, and means adjusting the pivoting of the rear links and the triangular links.

3. An excavating bucket including a cen-

tral shaft, a pair of scoops, front links connecting the shafts to the inner edge of the scoops, triangular links pivoted to the front links having their free ends pivotally connected, the rear links connected to the corners of the triangular links and the rear of the scoops, the said triangular links having a plurality of apertures therein by means of which the pivoting point of the rear links thereto may be adjusted.

4. An excavating bucket including a central shaft, a pair of scoops, front links connecting the shaft with the pair of scoops, triangular links pivoted to the front links, a shaft pivotally connecting the free ends of the triangular links having sheaves thereon, rear links connecting the corners of the triangular links with the rear of the scoops, a plurality of sheaves on the main shaft, an opening rope connected to the main shaft and then extending around the sheave on the shaft 70 which pivotally connects the triangular links and then extending upwardly, and a closing rope operatively connected to the bucket.

5. An excavating bucket including a central shaft, a pair of scoops, front links connecting the shaft with the pair of scoops, triangular links pivoted to the front links, a shaft pivotally connecting the free ends of the triangular links having sheaves thereon, rear links connecting the corners of the triangular links with the rear of the scoops, a plurality of sheaves on the main shaft, an opening rope connected to the main shaft and then extending around the sheave on the shaft which pivotally connects the triangular links and then extending upwardly, pulleys on the front links and a closing rope connected to the pulley of one front link then extending across over the pulley on the opposite front link, then back over the first mentioned pulley 90 and upwardly over one of the pulleys and the main shaft.

In witness whereof I have hereunto set my hand in the presence of two witnesses.

WILLIAM CLARK MITCHELL.
